[57] **CLAIM**

The ornamental design for a light fixture, as shown and described.

DESCRIPTION

FIG. 1 is a perspective view of a single lens light fixture in accord with our new design,

FIG. 2 is a top plan view of the light fixture of FIG. 1, FIG. 3 is a side elevational view of the single lens light fixture of FIG. 2 as taken from the bottom of FIG. 1, the opposite side elevational view being the mirror image thereof,

FIG. 4 is an end elevational view of the single lens embodiment of the design as taken from the right of FIG. 2,

FIG. 5 is an end elevational view as taken from the left of FIG. 2,

FIG. 6 is a perspective view of a double lens embodiment of a light fixture in accord with our new design,

FIG. 7 is a plan view of the double lens embodiment, FIG. 8 is a side elevational view as taken from the bottom of FIG. 7, the opposite side thereof being identical thereto; and,

FIG. 9 is an end elevational view of the double lens light fixture embodiment as taken from the right end of FIG. 7, the opposite end being identical thereto.
